UNITED STATES PATENT OFFICE.

FREDERICK C. REDMAN, OF NORTH ANDOVER, AND HENRY N. COLMAN, OF LAWRENCE, MASSACHUSETTS, ASSIGNEES TO DAVIS & FURBER MACHINE COMPANY, OF NORTH ANDOVER, MASSACHUSETTS, A CORPORATION OF MASSACHUSETTS.

STRIP-SKIVING APPLIANCE.

Application filed August 9, 1926. Serial No. 128,048.

This invention relates to a simple form of appliance for skiving strips of leather and similar material, such for example, as the tapes of a tape condenser. The appliance is small and compact and may be employed without removing the tapes from the condenser when it is desired to repair or splice the tapes.

The object of the invention is to provide such an appliance of simple construction and one which may be readily operated manually by anyone having the care of a machine employing such strips or tapes.

These and other objects and features of the invention will appear more fully from the accompanying descriptions and drawings and will be particularly pointed out in the claims.

The drawings illustrate a simple and preferred form of appliance particularly useful in skiving comparatively narrow strips of material such as the tapes of tape condensers already mentioned where no great amount of power is required to effect the skiving operation.

In the drawings:

Fig. 1 is a top plan view of the appliance with a strip in position and partially skived.

Fig. 2 is a view showing a section of the tape with the skived ends spliced together.

Fig. 3 is a view chiefly in central vertical cross section of the construction shown in Fig. 1.

Fig. 4 is a view partially in side elevation and partially in central vertical cross section of the appliance with the parts positioned near the end of the skiving operation.

Fig. 5 is a view chiefly in transverse cross section taken on the line 5—5 of Fig. 1.

This appliance is particularly designed for the skiving of comparatively narrow strips such as leather tapes of a tape condenser where the ends of the tapes are spliced together in the formation or repair of the tapes. A portion of such a tape is shown in Fig. 2 where the skived or wedge shaped end 1 is shown overlapping the skived or wedge shaped end 2.

The appliance in the preferred form illustrated comprises a base 3 formed preferably of metal and presenting an upstanding support herein shown as the vertical webs 4 extending upwardly on each side of the base. These webs constitute the support for the skiving knife. This knife has a flat body 5

and a bevelled cutting edge 6. The body is slotted at 7 and set screws 8 pass through these slots into the supporting flanges 4 and secure the knife firmly in an adjusted position with the edge extending transversely of and above the base. In order to position the knife accurately, stop plates 9 are secured by set screws 10 at the forward end of the flanges 4 so that the knife when in position has its cutting edge extending beneath and abutting these plates.

The base 3 is grooved longitudinally thus leaving the narrow side flanges 11 extending longitudinally at each edge of the base. Within the groove between these flanges is mounted a slide bar 12 also of metal. This bar at its rear end 13 is vertically wedge shaped. A roll device rests upon this slide bar beneath and parallel with the knife edge and this roll device is mounted on the upstanding support of the base for rotary movement and for vertical bodily movement. In the preferred construction illustrated this roll device is composed of an even number plurality, herein shown as two, superimposed rolls 14 arranged in vertical alignment beneath and parallel with the knife edge. The ends or journals of these rolls extend into vertical slots in the supporting flanges 4 so that the rolls are free to rotate and also free to move bodily in a vertical direction. The lowermost roll rests against the slide bar 12 and the uppermost against the strip 15 of material to be skived, thus during the skiving operation the roll peripheries in engagement respectively with the slide bar and with the strip travel in the same direction with both so that there is no drag either between the uppermost roll and the strip or the lowermost roll and the slide bar.

A suitable strip clamp is secured to the slide bar forward of the knife. This clamp is shown as a bracket 16 secured by set screws 17 to the slide bar and provided with upstanding flanges 18. A bar 19 serrated on its under face is secured to these flanges by the set screws 20. A bar 21 serrated on its upper face is guided between the flanges 18 and has a vertical stud 22 with a lower bevelled face 23 mounted in a vertical aperture in the bracket 16. A set screw 24 inserted transversely in the side of the bracket 16 has a conical end engaging the bevelled face 23.

It will thus be seen that by turning the set screw 24 the bar 21 will be raised or lowered to clamp or release the strip 15.

The longitudinal sliding movement of the slide bar 12 in the base is effected manually in any suitable manner. Preferably a lever 5 is fulcrumed at 26 on the rear end of one of the flanges 11 of the base and a link 27 is connected at one end at 28 to this lever and at the other end to a stud 29 secured midway 10 of the slide bar. A thumb piece 30 is provided secured to the side of the base so that the operator placing his thumb against this thumb piece and his fingers over the handle 15 of the lever 25 may readily exert the force required to move the slide bar and effect the skiving operation.

At the forward end of the base a cross bar 31 is provided secured by set screws 32 to the flanges 11 of the base to hold down and guide 20 the slide bar.

It will be seen that as the slide bar is moved forwardly or to the left, with the strip 15 clamped to the slide bar and extending over 25 the uppermost roll 14, that as the wedge shaped portion 13 of the slide bar forces the rolls 14 bodily vertically upward, the skiving knife will cut through the strip at the required angle.

30 In order to vary the skiving angle there is preferably provided a resilient bearing plate of metal 33 located in the groove of the base and extending between the base and slide bar. This bearing plate is secured as by 35 a rivet 34 at its forward end to the base. A set screw 35 threaded vertically through the base at the rear end abuts the bottom face of the bearing plate 33. Consequently by adjusting the set screw 35 the bearing plate may 40 be raised more or less at its rearward end as shown in Fig. 4, thus correspondingly raising the wedge shaped end 13 of the slide bar and varying the skiving angle. Either or both 45 the wedge shaped feature 13 of the slide bar and the vertically adjustable resilient plate may be employed as desired to produce the required skiving angle.

It will be seen that the device is small and compact and that it may be readily used to 50 skive the end of a tape or belt without removing the tape or belt from any machine upon which it may be in use, a feature which is of great advantage.

Having thus described the invention, what 55 is claimed as new, and desired to be secured by Letters Patent, is:

60 1. A strip skiving appliance comprising, a base having an upstanding support, a knife secured to the support with its edge transversely of and above the base, a bar mounted to slide longitudinally on the base, a resilient bearing plate secured to the base at its for-

ward end and extending between the base and the slide bar, means for adjusting vertically of the base the rear end of the bearing 65 plate, a roll device resting on the slide bar beneath and parallel with the knife edge and mounted on the support for rotary and vertical bodily movement, a strip clamp on the slide bar forward of the knife, and means 70 for moving the slide bar longitudinally on the base to skive a strip held in the clamp and resting on the roll device.

2. A strip skiving appliance comprising, a 75 base having an upstanding support, a knife secured to the support with its edge transversely of and above the base, a bar mounted to slide longitudinally on the base, a resilient bearing plate secured to the base at its forward end and extending between the base 80 and the slide bar, means for adjusting vertically of the base the rear end of the bearing plate, an even number plurality of superimposed rolls arranged in vertical alignment 85 beneath and parallel with the knife edge and mounted on the support for rotary and vertical bodily movement with the lowermost roll resting against the slide bar and the uppermost against the strip during the skiving operation whereby the roll peripheries thus 90 in engagement with the slide bar and strip travel in the same direction therewith, a strip clamp on the slide bar forward of the knife, and means for moving the slide bar longitudinally on its base to skive a strip held in 95 the clamp resting on the roll device.

3. A strip skiving appliance comprising, a base having an upstanding support, a knife secured to the support with its edge transversely of and above the base, a bar having a vertically wedge shaped rear end mounted 100 to slide longitudinally on the base, a roll device resting on the slide bar beneath and parallel with the knife edge and mounted on the support for rotary and vertical bodily movement, a strip clamp on the slide bar forward of the knife, a lever connected to the base and to the slide bar and presenting a handle projecting laterally from the base in 105 position to be grasped by the hand and operated to effect the longitudinal movement of the slide bar to skive a strip held in the clamp and resting on the roll device.

4. A strip skiving appliance having construction defined in claim 3 together with a thumb piece on the forward end of the base to receive the thumb of the hand grasping the handle and thus assist in the operation of the lever.

In testimony whereof, we have signed our 120 names to this specification.
